UNITED STATES PATENT OFFICE.

KAROL BRZYSKI, OF PHILADELPHIA, PENNSYLVANIA.

SHIP'S ARMOR.

1,289,639.

Specification of Letters Patent.

Patented Dec. 31, 1918.

Application filed May 14, 1918. Serial No. 234,444.

To all whom it may concern:

Be it known that I, KAROL BRZYSKI, a citizen of Austria, Galicia Poland, residing at Philadelphia, in the county of Philadelphia 5 and State of Pennsylvania, have invented new and useful Improvements in Ships' Armor, of which the following is a specification.

This invention relates to armor adapted 10 to be applied to the sides of a ship or vessel for protecting the same against torpedo attacks. It consists in the novel features hereinafter described and claimed.

An object of the invention is to provide 15 an armor of the character stated which is of substantial structure and which will occupy but minimum space at the side of the vessel and consequently will not interfere with the navigation or propulsion of the same.

20 With this object in view the armor comprises a plate adapted to be applied to the side of the vessel and it lies in close proximity thereto. Curved plates are secured at their edge portion to the upper and lower 25 edge parts of the first mentioned plate and the inner portions of the said curved plates are connected together by a pointed coupling strip the same being provided at its edges with off-set flanges to which the said curved 30 plates are attached by means of bolts or other suitable securing devices. The armor is adapted to extend along the sides of the vessel and around the bow and stern thereof and below the water line. The end portions 35 of the armor at the forward and end portions of the vessel are pointed and the plates are so arranged that in the event that a torpedo approaches them and strikes it is deflected either in an upward direction or a 40 downward direction and the resulting explosion extends its force exteriorly of the vessel inasmuch as the torpedo is prevented from penetrating the sides.

In the accompanying drawings:

45 Figure 1 is a side elevation of a vessel with the armor applied.

Fig. 2 is a detailed sectional view of the same.

50 Fig. 3 is a fragmentary longitudinal sectional view.

Fig. 4 is a detail perspective of the coupling strip.

Fig. 5 is a sectional view through one of the ends of the armor.

55 The armor comprises a plate 1 adapted to be applied to the side of a ship or vessel

and secured in place by means of suitable bolts indicated at 2. A curved plate 3 is secured to the upper portion of the plate 1 by means of bolts 4 which pass through the 60 plate 3 at points spaced from the upper edge thereof whereby the upper edge portion of the plate 3 is spaced from the upper edge of the plate 1 as best shown in Fig. 2, of the drawings. A curved plate 5 is secured by 65 means of bolts 6 to the lower portion of the plate 1 and the lower edge portion of the plate 5 lies in close proximity to the outer surface of the plate 1. A bracket rail 7 may be applied to the side of the vessel and 70 against which the lower edges of the plates 1 and 5 may rest for holding the said plates in proper position. A coupling strip 8 connects the outer ends of the plates 3 and 5 together and the side portions of the said strip 75 are disposed at an acute angle with relation to each other whereby a line or edge is provided at the intermediate portion of the said coupling strip. The said coupling strip is provided at its edge portions with offset 80 flanges 9 to which the outer edges of the plates 3 and 5 are attached by means of bolts 10. Therefore the outer surfaces of the plates 3 and 5 are substantially flush with the outer surfaces of the angularly disposed 85 portions of the coupling strip 8.

The armor as described extends along the intermediate portion of the body of the vessel and is submerged below the water level. The armor at the forward and rear ends of 90 the vessel is pointed as best shown in Fig. 1 and the outer plates may be convexed and inasmuch as they extend from the upper to the lower edge portions of the plate 1 the coupling strip 8 as hereinbefore described 95 may not be used at the forward and rear ends of the vessel.

Inasmuch as the armor is submerged below the surface of the water in event that a torpedo approaches the same and strikes its 100 nose will pass along the upper or lower side of the coupling strip 8 and consequently the torpedo will be deflected from a horizontal position to an inclined position and when the explosion takes place its force will 105 be expended exteriorly of the hull of the vessel in view of the fact that the end of the torpedo is prevented from penetrating the side.

The upper portion of the plate 3 is spaced 110 from the upper portion of the plate 1 to deflect the point of the torpedo in a down-

ward direction in event that the torpedo approaches immediately at the surface of the water.

In the event that the torpedo strikes the armor at the forward or rear end portion of the vessel it will be deflected laterally by the curvature of the exterior plate and consequently when the explosion takes place the force will be expended in front of or at the rear of the body of the vessel and consequently little or no damage will result.

From the foregoing description taken in conjunction with the accompanying drawings it will be observed that a ship's armor 15 of simple and durable structure is provided and that the same may be used to advantage for effectually protecting a ship or vessel against torpedo attack.

Having described the invention what is 20 claimed is:

1. An armor comprising a plate adapted to be applied to the side of a vessel, curved plates connected at their edge portions with the first mentioned plate and a coupling 25 strip connecting the outer edges of the curved plates together said coupling strip being provided with angularly disposed side portions.

2. An armor comprising a plate adapted 30 to be applied to the side of a vessel, curved plates connected at their edge portions with the edges of the first mentioned plate, a coupling strip having offset flanges con-

nected with the outer portions of the curved plates the said coupling strip being provided with angularly disposed side portions. 35

3. An armor comprising a plate adapted to be applied to the side of a vessel, curved plates connected at their edge portions with the edge portion of the first mentioned plate, 40 one of the said curved plates having an edge portion spaced from the adjacent surface of the first mentioned plate and a coupling strip connecting the outer portions of the curved plates together said coupling strip 45 being provided with angularly disposed side portions.

4. An armor comprising a plate adapted to be applied to the side of a vessel, curved plates connected at their edge portions with 50 the edge portions of the first mentioned plate, one of the said curved plates being provided with an edge portion which is spaced from the adjacent surface of the first mentioned plate, a coupling strip having 55 angularly disposed side portions and provided with a longitudinally disposed edge, said coupling strip having offset flanges at its edges and means for securing the said flanges to the outer portions of the curved 60 plates whereby the outer surfaces of the curved plates are substantially flush with the exterior surfaces of the side portions of said coupling strip.

In testimony whereof I affix my signature. 65
KAROL BRZYSKI.
